(57) **CLAIM**

The ornamental design for a propane tank transport stabilizer, as shown and described.

DESCRIPTION

FIG. 1 is a perspective view of a propane tank transport stabilizer showing our new design, wherein a partial view of a propane tank is shown in broken lines for illustrative purposes only and forms no part of the claimed design;

FIG. 2 is a bottom view thereof;

FIG. 3 is a front view thereof;

FIG. 4 is a right side view thereof;

FIG. 5 is a rear view thereof;

FIG. 6 is a left side view thereof;

FIG. 7 is a cross-sectional view along the line 7—7 of FIG. 5; and,

FIG. 8 is a top view thereof.
